EGISTO BIFFI, OF LECCO, ITALY.

PERCUSSION-FUSE FOR PROJECTILES.

1,322,521.

Specification of Letters Patent. Patented Nov. 25, 1919.

Application filed October 17, 1918. Serial No. 258,656.

To all whom it may concern:

Be it known that I, EGISTO BIFFI, a citizen of the Kingdom of Italy, residing at Lecco, Italy, have invented certain new and useful 5 Improvements in Percussion-Fuses for Projectiles, of which the following is a specification.

The present invention relates to a new kind of percussion fuse for projectiles in 10 general and particularly applicable to projectiles termed hand grenades which constitute the ordinary weapons of the trenches and the invention is intended to obtain the following objects with the greatest certainty 15 and efficacy.

1. Such means and methods of safety as will entirely obviate deflagrations or accidental spontaneous explosions either in storing or in handling the projectile.

20 2. A method of automatically controlling the firing-pin so that the action thereof and consequently the explosion of the projectile may be made inevitable and be absolutely assured whatever revolution it may effect in 25 its flight.

The idea of the invention will be easily understood by referring to the accompanying drawings which illustrate by way of example one method of carrying out the invention applied to a hand grenade and in 30 which:

Figure 1 shows on an enlarged scale the grenade referred to in the position of safety and in vertical section through its center.

35 Fig. 2 is a front view of the upper part.

Fig. 3 shows the grenade in the ideal explosion position that is to say after striking the object aimed at in vertical section through its center.

40 Fig. 4 is a section along the line $-x-x-$ in Fig. 1 and finally

Fig. 5 is an elevation on a smaller scale.

In the drawings the same numerals indicate the same parts.

45 The grenade referred to consists of the cylindrical body $-1-$ which may be made of sheet-iron, cast-iron, or steel and contains the chamber for the explosive $-2-$.

Screwed at $-3-$ on to the body $-1-$ 50 is the diaphragm or platform $-4-$ the lower part of which is furnished with a tubular appendix $-13-$ which serves as a guard for the firing-pin $-14-$, while above the safety and bursting device is mounted.

To the diaphragm $-4-$ a cap $-5-$ is 55 fixed.

The arrangement under consideration consists of two supports fixed to the base $-4-$ on which the pincers $-8-$ are mounted so as to pivot around $-7-$ these pincers being furnished with bilateral jaws $-9-$, $-10-$ for the purpose of holding the ball $-11-$ and the head $-12-$ of the firing-pin $-14-$ respectively. $-15-$ is an antagonistic spiral spring arranged so as to 60 allow the striking-pin to act when left to itself.

Screwed on to the cylinder $-13-$ is a small tube $-16-$ for the percussion cap $-17-$ and the detonating substance $-18-$.

70 For the protection of the percussion cap $-17-$ a small tin disk $-19-$ and a retaining ring $-20-$ are provided.

In order to maintain the striking pin $-14-$ in the position of safety a pin $-21-$ 75 is provided which runs through and firmly holds together the cap, the arms of jaws $-9-$ and the ball $-11-$ so as to prevent the opening of the jaws $-10-$ and consequently the release of the head $-12-$ of 80 the striking pin $-14-$.

A forked stop $-22-$ introduced through the opening $-25-$ between the head $-12-$ and the diaphragm $-4-$ serves as a subsidiary safety device. The said forked stop $-22-$ is furnished externally with an extension $-23-$ which, by means of a ring $-24-$ held in place by the pin $-21-$, insures its stability when the projectile is at 85 rest.

In order to prevent the said stop $-22-$ leaving its seat prematurely on the projectile being thrown and after the pin $-21-$ and ring $-24-$ have been removed, a small rope $-26-$ is provided. One end of this 90 rope is secured at $-27-$ to the extension $-23-$, and the other end, after making two or three turns around the projectile body, is secured to a plate $-28-$ arranged in a 95 similar manner to the extension $-23-$.

100 It is evident that these subsidiary stop devices serve and are meant to operate solely in case of accidental shocks occurring in the handling of the grenade after the removal of the pin $-21-$. In any case the arrangement of the spring $-15-$ relatively to the reaction to be exercised on the jaws $-10-$ in order to prevent the loosening of the 105

striking pin —14— is such that the ball —11— remains in place.

The operation is as follows:

After the grenade has been seized with the right hand, the thumb pressing the plate —28—, the safety pin —21— and the ring —24— are removed and the grenade is launched. In its flight the plate —28— will automatically detach itself by gravity dragging along with it, after a time interval dependent on the unwinding of the rope —26—, the stop fork —22—. On the grenade now striking against an obstacle, through inertia, the ball —11— will be released from the jaws —9— and through the action of the spring —15— will cause the jaws —10— (Fig. 3) to open and the successive and simultaneous action of the striking pin —14— by striking the percussion cap will explode the detonating material —18— and consequently the charge of powder in the chamber —2—.

It is understood that the details of construction may vary in practice without going beyond the limits of the invention.

Having now particularly described and ascertained the nature of my said invention

and in what manner the same is to be performed I declare that what I claim is:

A percussion fuse for projectiles comprising a projectile body, a tensioned firing pin, pincers pivoted on depending portions of the interior of the projectile body, arms on said pincers, jaws on said arms for gripping the head of said tensioned pin, a member frictionally engaged between said arms to keep the jaws in gripping position, a catch for said firing pin having an outwardly extending portion bent over the exterior surface of the projectile body, a plate bearing against the exterior surface of the projectile body, a rope coiled around the projectile body over said extension and said plate with its ends joined to them, a ring linking together said plate and said extension, and a stoppin lodged in the projectile body and crossing the member and engaged between the arms above said pincers.

In testimony whereof I affixed my signature in presence of two witnesses.

EGISTO BIFFI.
